The ornamental design for a closure for a container, as shown and described.

DESCRIPTION

FIG. 1 is a top, front and right side isometric view of a closure for a container shown in a closed position;

FIG. 2 is a top, rear and right side isometric view thereof rotated about 90° from the view shown in FIG. 1;

FIG. 3 is a top plan view thereof;

FIG. 4 is a front elevational view thereof;

FIG. 5 is a rear elevational view thereof; and,

FIG. 6 is a right side elevational view thereof, the left side elevational view thereof being a mirror image.

The bottom view forms no part for the claimed design.

The broken lines in FIGS. 2, 3, 5 and 6 depict portions of the closure for a container that form no part of the claimed design.
